UNITED STATES PATENT OFFICE.

CHARLES H. SCOTT, OF MINNEAPOLIS, MINNESOTA.

ATTACHMENT FOR GRAIN-CLEANING MACHINES.

No. 918,095.

Specification of Letters Patent.

Patented April 13, 1909.

Application filed December 10, 1906. Serial No. 347,076.

To all whom it may concern:

Be it known that I, CHARLES H. SCOTT, of Minneapolis, Hennepin county, Minnesota, have invented certain new and useful 5 Improvements in Attachments for Grain-Cleaning Machines, of which the following is a specification.

My invention relates to grain-cleaning machinery, and the object of the invention is to 10 provide means for keeping the meshes of a sieve clear to facilitate the grain cleaning operation.

A further object is to provide a means for 15 cleaning the upper surface of a sieve without damaging the meshes thereof.

My invention consists generally in a 20 scraper operating on the upper surface of the sieve and arranged to keep it clean without interfering with the passage of the grain therover.

In the accompanying drawings, forming 25 part of this specification, Figure 1 is a plan view of a portion of a grain cleaning machine with my invention applied thereto. Fig. 2 is a partial side elevation of the same. Fig. 3 is a vertical sectional view showing the position of the scraper devices on the sieves. Fig. 4 is a detail view showing the manner of 30 mounting the scraper. Fig. 5 is a sectional view of the same.

In the drawing, 2 represents the frame of 35 the machine and 3 a sieve mounted therein and upon which the grain to be cleaned is discharged. I make no claim to any particular form of machine or sieve as my invention is applicable to any style now in use, suitable 40 modifications being made in the manner of mounting the device to adapt it to the different types of machines.

45 In Fig. 1, I have shown one form of mounting which consists in providing angle bars 4 secured to the frame of the machine and forming guides for frames 5 that are adapted to slide horizontally between them. These frames consist preferably of tubes 50 threaded and secured together and having shoes 6 secured to the frame by set screws 7 or other suitable means to permit their adjustment on said frame so that it will run 55 easily and smoothly between the guides. I have shown in Fig. 1 two sets of these frames arranged to move across the sieves, one set traveling in one direction while the other set is traveling in the other direction. A chain 60 65 8 or other flexible means connects the frames at one end, passing around anti-friction

wheels 9. A similar chain is provided on the other side of the machine and a sprocket chain drive 10 is attached to said lastnamed chain and forms a driving means for the 60 scraper frames. This driving device forms the subject matter of an application for United States Patent, filed September 27, 1904, No. 226,101, and requires no detailed description herein. Upon each frame I provide a series of hangers 11 loosely mounted between adjustable collars 12, and springs 13 are looped around said frames between said collars and said hanger and have one end 65 arranged to bear on the lower portion of said hanger, one spring on one side and the other on the other, and the tension of these springs tends to hold the hanger in a vertical position, each spring yielding, however, to allow the hanger to be swung either forwardly or 70 backwardly. Any other suitable form of spring for yieldingly retaining the hangers 11 in a substantially vertical position, may be 75 used in place of those described.

Upon the lower end of the hanger 11 is a 80 scraper 14 consisting preferably of a narrow, comparatively thin band of metal that is adapted to sweep over the upper surface of the screen and prevent the chaff and refuse material from lodging therein and keeping 85 the meshes clean, while without in any way interfering with the movement of the grain thereon. The scraper as shown in the drawing is quite narrow so that in sweeping over the sieve the grain instead of being pushed along ahead of the scraper will flow back over 90 its upper edge and the passage of the grain down over the sieve will practically be uninterrupted. In case a nail or any piece of foreign material catches in the meshes of the 95 sieve the yielding blade engaging the same will slip or ride over it without damaging the sieve, whereas if a rigidly mounted scraper should be employed and it came in contact with any foreign substance sticking in the sieve the meshes would be torn or damaged. The yielding character of my scraper, however, obviates all danger of damage to the 100 sieve in this way.

I do not wish to be confined to any particular form of scraper employed as it is capable of many modifications. I prefer, however, the narrow thin blade shown, as I believe it will be more suitable than any other form for the purpose.

105 110 It will be understood, of course, that any number of these scrapers and blades may be

used on a machine according to its size and the length of the sieves and hence I do not wish to be confined to the particular number or arrangement herein shown.

5. I claim as my invention:

1. The combination with a sieve, of a narrow scraper arranged to reciprocate thereon, a support for said scraper, there being an unobstructed space between said scraper and 10 said support through which the material may flow backwardly over said scraper, substantially as described.

2. In a grain cleaning machine, the combination with a sieve, of a narrow scraper operating thereon, a support for said scraper, means whereby said scraper will yield under backward pressure thereon, and rising slightly clear an obstruction in the sieve, substantially as described.

20 3. In a grain cleaning machine, the combination, with a sieve, of a series of scraper blades arranged edgewise on the surface of the sieve, and means for reciprocating said blades on said sieve, said blades allowing the 25 free passage of the grain and being capable of yielding upon striking obstructions in the sieve.

4. In a grain cleaning machine, the combination with a reciprocating frame, of hangers loosely mounted thereon, springs carried by said frame and engaging said hangers and yieldingly preventing movement of the same in either direction and narrow scraper blades carried by said hangers and adapted to 35 sweep across the upper surface of the sieve the tops of said blades being sufficiently near the sieve to allow the grain to flow back thereover, substantially as described.

5. In a grain cleaning machine, the combination, with a sieve, of a scraper consisting of a comparatively narrow flat blade arranged to reciprocate thereon and means for operating said scraper, the lower edge of the scraper bearing on said sieve and said 45 scraper being yieldingly mounted, whereby it will ride over an obstruction in the sieve, without breaking the meshes thereof.

6. In a grain cleaning machine, the combination with the sieves, of reciprocating frames and means for guiding the same, and 50 comparatively narrow scrapers carried by said frame and adapted to sweep across the surfaces of said sieves and said scrapers being yieldingly mounted on said frames, whereby independent movement of each of said 55 scrapers to accommodate itself to an obstruction on the sieve, is permitted, for the purpose specified.

7. In a grain-cleaning machine, the combination, with a sieve, of a frame slidably 60 mounted above the same, arms depending from said frame and arranged to oscillate forward and back thereon, means for yieldingly resisting the oscillation of said arms, and scraper blades carried by said arms and 65 arranged to sweep over said sieve and through the grain thereon, substantially as described.

8. The combination, with a sieve, of oscillating arms and means supporting the same, 70 means for yieldingly resisting the oscillation of said arms forward and back, and narrow metallic blades carried by said arms and arranged to sweep over said sieve and through the grain thereon, substantially as described. 75

9. In a grain cleaning machine, the combination, with a sieve, of a frame arranged to reciprocate above the same, hangers yieldingly mounted on said frame and narrow scrapers carried by said hangers and arranged to bear on the sieve, said scrapers being capable of yielding horizontally with said hangers upon striking an obstruction in the sieve, and the upper edges of the scrapers being close to the surface of the sieve, whereby 80 the grain will flow back thereover instead of being pushed ahead of the scrapers, substantially as described. 85

In witness whereof, I have hereunto set my hand this 5th day of December 1906.

CHARLES H. SCOTT.
